UNITED STATES PATENT OFFICE.

PERCIVAL S. MORRIS, OF BROOKLYN, NEW YORK.

FOUNTAIN PEN AND PENCIL.

Application filed August 12, 1922, Serial No. 581,446. Renewed November 20, 1926.

This invention contemplates the provision of a combined fountain pen and lead pencil embodying a valve including a tubular stem of a size to accommodate the lead, the stem being utilized to adjust the valve toward and away from its seat, and to control a sliding disk which moves in one direction to create a suction for the purpose of filling the pen.

10 Another object of the invention resides in the provision of an article of the character above mentioned, wherein the cap of the pen is provided with a bore for the reception of an eraser, means being provided to normally 15 close the bore and conceal the eraser within the latter, and the means is utilized in holding the eraser in a projected position for use.

The nature and advantages of the invention will be better understood when the following detailed description is read in connection with the accompanying drawing, the invention residing in the construction, combination, and arrangement of parts as claimed.

25 In the drawing forming part of this application, like numerals of reference indicate similar parts in the several views, and wherein:—

Figure 1 is a longitudinal sectional view 30 through the pen and pencil.

Figure 2 is a transverse sectional view taken on line 2—2 of Figure 1.

Figure 3 is an end elevation.

Figure 4 is a detail view of the lead holding clamp.

Referring to the drawing in detail, 10 indicates the barrel of the pen which is threaded at one end as at 11 to accommodate the holder 12 and the nib 13. The opposite end of the barrel is reduced and threaded as at 14 and is received by a substantially conical shaped cap 15 through the small end of which projects the strip of lead 16. This end of the article is used as a lead pencil, while the opposite end is used as a fountain pen and the pen point and holder therefor are normally concealed within the usual cap 17 provided with a spring clip 18. The cap 17 is provided with a bore 19 which opens at one end of the cap to slidably receive a tubular eraser 20, which is wholly disposed within the bore 19 when not in use. When the eraser is wholly arranged within the bore 19, the outer end of the bore is closed by a pivoted cover 21 which has a cam-like portion 22. When it is desired to use the eraser, the cover 21 is swung to a perpendicular position, and the article inverted to allow the eraser to slide from within the bore 19 an appreciable distance, 60 and when properly positioned, the cover 21 is swung to the position illustrated in Figure 1, wherein the cam surface 22 forces and holds the eraser 20 against the threads of the bore 19.

Arranged within the barrel 10 is a hollow tubular member 23 constituting the stem of a valve 24 which is adapted to move toward and away from its seat 25 formed on the pen point holder 12. This holder is also provided with a pocket 26 to receive a quantity of ink from the barrel and by regulating the valve with relation to its seat any particular quantity of ink may be admitted to the pocket 26. The stem 23 as hereinabove stated receives the lead 16. This stem is also provided with fast and slow threads 27 and 28 respectively, the latter engaging the interior threads formed on the reduced portion 14 of the barrel. Associated with the threaded portion 28 of the stem is a threaded sleeve 29 which is formed at one end with a plurality of resilient fingers 30, the latter being positioned within the cap 15 and held by the latter in effective engagement with the lead 16 to hold the latter in a given position. It will be readily understood that by simply loosening the cap 15 or wholly removing the same from the reduced end of the barrel 10, the resilient fingers automatically move away from the lead 16 to allow the latter to be properly adjusted for use, and when the cap 15 is tightened, it moves against the resilient fingers and causes them to clip the lead 16 to 70 hold it fixed with relation to the cap. By turning the stem 23 within the reduced portion 14 of the barrel, the valve 24 is moved toward or away from its seat. The interior of the barrel is provided with opposed longitudinal ribs 31, which are received by notches formed in the periphery of a disk 32. This disk is mounted on the stem for sliding movement, and when the stem is turned, the fast threads 27 cause the disk to move longitudinally within the barrel. The disk is used to fill the fountain pen, inasmuch as when the disk is moved from one end of the pen to the other, it creates a suction which draws the ink into the barrel.

While it is believed that from the foregoing description, the nature and advan-

tages of the invention will be readily apparent, I desire to have it understood that I do not limit myself to what is herein shown and described, and that such changes 5 may be resorted to when desired as fall within the scope of what is claimed.

What I claim is:—

A fountain pen comprising a barrel, a pen 10 receiving element carried by one end thereof and having an ink receiving pocket, also a valve seat, a tubular stem extending longitudinally through the barrel and rotatably mounted therein for manual rotation, a valve carried by the stem and adapted to seat on

the valve seat, longitudinal ribs formed 15 upon the inner face of the barrel at diametrically opposite points, a spiral thread on the stem, a disk provided with notches at diametrically opposite points and slideable on the ribs and having threaded engagement 20 with the spiral thread whereby upon rotation of the stem the disk will be moved away from the ink receiving pocket to create a vacuum in the barrel to fill the pen, such rotation of the stem simultaneously moving 25 the valve away from the valve seat.

In testimony whereof I affix my signature.
PERCIVAL S. MORRIS.
